UNITED STATES PATENT OFFICE.

ABRAHAM H. SHENK, OF JOLIET, ILLINOIS.

DESIGN FOR A TOY.

61,214.

Specification for Design.

Patented July 11, 1922.

Application filed November 25, 1921. Serial No. 517,797. Term of patent 3½ years.

To all whom it may concern:

Be it known that I, ABRAHAM H. SHENK, a citizen of the United States, and resident of Joliet, in the county of Will and State of Illinois, have invented a new, original, and ornamental Design for a Toy, of which the following is a specification, reference being had to the accompanying drawing, forming a part thereof.

Fig. 1 is a front view of the toy, and
Fig. 2 is a side view thereof.

I claim:

The ornamental design for a toy, as shown.

ABRAHAM H. SHENK.
